No. 36,514.

Patented August 25, 1903.

UNITED STATES PATENT OFFICE.

JOHN C. IRVINE, OF SAN FRANCISCO, CALIFORNIA.

DESIGN FOR A BADGE.

SPECIFICATION forming part of Design No. 36,514, dated August 25, 1903.

Application filed July 23, 1903. Serial No. 166,782. Term of patent 14 years.

To all whom it may concern:

Be it known that I, JOHN C. IRVINE, a citizen of the United States, residing at San Francisco, in the county of San Francisco and State of California, have invented a new, original, and ornamental Design for a Badge, of which the following is a specification, reference being had to the accompanying drawing, forming part thereof.

10 The drawing illustrates my design.

I claim—

The ornamental design for a badge, as shown.

In testimony whereof I affix my signature in the presence of two witnesses.

JOHN C. IRVINE.

In presence of—

MATTHEW BRADY,
H. G. CRAIG.
